UNITED STATES PATENT OFFICE

2,599,102

AUTOMOBILE ENGINE BELT TOOL

J.D. Gilbreath, Alpine, Tex.

Application March 15, 1949, Serial No. 81,427

1 Claim. (Cl. 254—99)

1

This invention relates to novel and useful improvements in tools, particularly those adapted for special jobs as opposed to general utility tools.

An object of this invention is to tighten the generator belt and fan belt selectively or tighten both of them simultaneously.

Another object of this invention is to mount a support on less than one-half the peripheral surface of the water pump pulleys of an engine and to move vertically an adjustable element which carries a chain or other element having one or more clamps thereon, the clamps adapted to engage the under surface or portions of the engine accessories such as the under surface of the generator pulley or the bottom of the fan shaft, whereby the fan may be lifted, thereby tightening the proper belt and whereby the generator may be lifted, thereby tightening the appropriate belt.

Another purpose of this invention is to lift the generator and fan of certain types of engines, thereby tightening the attendant belts by means of a standard which has curved feet at the end thereof connected with the remainder of the standard by means of offsets so that the tightening may take place at a point spaced from the vertical plane of the two water pump pulleys, thereby avoiding interference with the actual belt being tightened when this operation is taking place.

Ancillary objects and features of novelty will become apparent to those skilled in the art, in following the description of the preferred form of the invention, illustrated in the accompanying drawings, wherein:

Figure 1 is the front view of an engine of a typical type having the invention applied thereto and in partial operation;

Figure 2 is a front view of the standard or support;

Figure 3 is an elevational side view of the device shown in Figure 2, showing schematically and in phantom a portion of an engine to illustrate the arrangement of the tool with respect to said engine;

Figure 4 is a fragmentary elevational view showing the arrangement of the generator pulley clamp on the said generator pulley;

Figure 5 is a longitudinal sectional view of the vertically adjustable element for lifting the clamps; and

Figure 6 is an elevational detail of construction showing particularly a means for spacing the generator belt a small amount from the pulley.

The present invention is adaptable for use in connection with various types of engines. Preferably, however, it is used in connection with engines of the V-type having a certain arrange-

ment of parts. This arrangement is shown in Figure 1, illustrating a popular make engine. There is disclosed, as conventional and old, both in structure and arrangement, an engine block 10 having heads 12 and 14 respectively, a timing case 16, motor mounts 18 and 20 and a crank shaft operated double sheave 22. A generator bracket 26 is attached to the engine block in the usual manner and there is a shaft supporting a fan pulley 28 carried by the generator bracket 26. A generator pulley 30 is attached to the shaft of the generator 32 in the usual manner. There is supplied in the illustration a pair of water pump pulleys 34 and 36 respectively which are mounted in a single vertical plane and which are horizontally spaced from each other as is conventional in certain types of engines.

A first belt 38 of conventional description is entrained around the two water pump pulleys 34 and 36, the double sheave 22 and the generator pulley 30. A second belt 40 also of conventional description is also entrained around the double sheave 22 and the fan pulley 28. It is sometimes necessary to tighten either the belt 38 or the belt 40 or both belts. Accordingly, a tool is provided for this purpose. The tool consists of a support or standard 42 having smoothly curved feet 44 and 46 respectively at the bottom thereof. The support 42 is made of a pair of legs 48 and 50 respectively which are firmly attached to a small case or housing 52 at one end and which have offsets 54 and 56 respectively at the opposite end. These offsets terminate in downwardly extending feet 46 and 44 respectively adapted to embrace something less than half of the peripheral surface of the water pump pulleys 34 and 36, respectively, and on the inside of the belt 38. The offset makes it possible to insert the tool and more specifically the standard or support 42 and leave working room so that the generator and generator pulley may be lifted.

The housing 52 has a shank 60 mounted for rotation therein and there are threads 62 thereon. A handle 64 may be disposed at the top end of the shank for facility in rotation. A threaded collar 66 is disposed within the housing 52 and it has a hook or projecting member 68 fixed thereto for vertical movement therewith. A slot 72 is formed in the side of the housing 52 with the projecting member 68 passed therethrough.

Accordingly, upon rotation of the shank 60, the collar 66 is lifted or lowered by means of the threaded connection between the two and the hook or projecting member 68 is raised or lowered, depending on which direction the shank is rotated.

A flexible member, such as a chain 76, is attached to the projecting member or hook 68 by

means of one of the links thereof. Of course, a cable may be used in lieu of the chain 76 or other equivalents may be substituted therefor. At one end of the chain 76 there is a specially designed clamp 80 adapted to engage the bottom or under surface of the generator pulley 30. The shape of the clamp is seen best in Figure 4 and consists of a rod bent to form an eye 82 at the top thereof and having offset portions 84 at the opposite ends thereof. A smoothly curved cradle member 86 is carried by the offsets or offset portions 84. It is this cradle member which is adapted to be disposed beneath the said pulley 30.

It is quite apparent that upon raising and lowering the hook 68, the belt 38 may be manipulated for tightening.

If it is desired to either simultaneously adjust the belt 40 or independently adjust the belt 40 with respect to the belt 38, this may be accomplished. A fastening element or clamp such as the hook 90 is attached at the opposite end of the chain 76. This clamp is adapted to be disposed below a portion of the fan assembly and to lift the same upon raising of the projecting member or hook 68.

Accordingly, in operation, either the fan belt pulley may be lifted or the generator pulley or both. It requires only a single manipulation of one handle 64 in order to raise the desired pulleys, thereby tightening the belts as necessary. Often the generator belt is pulled too tight, causing premature wear on the belt. To avoid this, it is only necessary to manipulate the adjustable elements 91 and 92 which are carried at the ends of the cradle member 86 and which a screw or cap screws. When the clamp 80 is in position below the generator pulley 30, the elements 91 and 92

will spread the belt slightly so that after fastening the generator in place on the engine, a proper amount of slack will remain in the belt 38.

It is apparent that variations may be made without departing from the spirit of the invention.

Having described the invention, what is claimed as new is:

For use with an engine which has a plurality of pulleys, a tool for tightening a belt entrained about the pulleys comprising a standard and a clamp, means carried by said standard and attached to said clamp for raising and lowering said clamp, the clamp including a curved cradle member adapted to detachably engage the lower surface of one of the pulleys, means carried by said standard for supporting said standard on portions of the periphery of at least two other pulleys, and adjustable members carried by said curved cradle member to engage said belt, whereby when said cradle member is lifted said adjustable members engage said belt and hold it spaced slightly from the pulley which is contacted by said curved cradle member.
